UNITED STATES PATENT OFFICE.

ALONZO B. SCOTT, OF FAIRMONT, WEST VIRGINIA.

CARD-HOLDING ATTACHMENT FOR PENCILS.

1,297,017.

Specification of Letters Patent. Patented Mar. 11, 1919.

Application filed October 18, 1918. Serial No. 258,735.

To all whom it may concern:

Be it known that I, ALONZO B. SCOTT, a citizen of the United States, and a resident of Fairmont, in the county of Marion and State of West Virginia, have invented a new and Improved Card-Holding Attachment for Pencils, of which the following is a description.

My invention relates to a card holding device and more particularly to means for holding an identification card such for example as a lodge card, or that of an officer or enlisted man in the Army or Navy, although the device may be employed for use in holding a calendar sheet or the like. The invention in its preferred form is especially designed for use in pencil cases of a known type.

The general object of the invention is to provide means applicable to a tubular interior element of a pencil or equivalent cylindrical element to hold a card in rolled form and housed within the case, my novel device having the advantage that the flexible card may be quickly secured at one end to the tubular element to be rolled thereon, while a restraining band forming part of the device is adapted to be slipped onto the rolled card to restrain the same against unrolling, and permitting of the card to be snugly housed within the pencil casing while preserving in the latter its normal appearance.

Other objects and advantages will appear as the description proceeds.

Reference is to be had to the accompanying drawings forming a part of this specification, it being understood that the drawings are merely illustrative of one example of the invention.

Figure 1 is a side elevation of a pencil, the case of which houses my improved attachment and the card held thereby;

Fig. 2 is a side elevation with the case removed, the card being held in rolled form;

Fig. 3 is a view similar to Fig. 2 with the card unrolled for reading;

Fig. 4 is a view similar to Fig. 3, but showing the opposite side of the holder and card;

Fig. 5 is a cross section on the line 5-5 Fig. 2;

Fig. 6 is a cross section on the line 6-6, Fig. 3.

My invention is shown as applied to a pencil of the type in which the lead 10 is

held in a lead tube 11 at the front of a tubular element 12, the rear end of which is in rigid relation to a head 13, forming the rear end of the pencil. A removable case 14 receives the front end of the head 13 and through the front end of which case the lead 10 is adapted to be projected by the turning of the head 13 relatively to said case, these features being generally common to pencils of known type. Near the front of the tubular element 12 is a collar or annular flange 15 and near the rear end at the front of the head 13 is a zone 16 corresponding with the collar 15, the opposed faces of the elements 15, 16, presenting shoulders by reason of their greater diameter relatively to the tube 12. On said tube 12 between the shoulders presented by the elements 15, 16 and within the cylindrical surfaces thereof, a flexible card A is adapted to be rolled, said card being adapted to receive the name and any other data desired.

Loosely surrounding the zone 16 is a band 17 preferably of unbroken continuity which is adapted to be slipped over the rolled card as indicated at Fig. 2. The rolled card forms part of the same cylindrical surface with the collar 15 and zone 16 and the band 17 may be readily slipped from the zone 16 onto the rolled card or from the card to the said zone 16 to permit the card to be readily unrolled as in Figs. 3 and 4 for reading. In order to hold the inner end of the card to the tube 12 or like cylindrical element, I provide a clip or clips 18 of semi-circular form and resilient to adapt them to be sprung onto the tube 12 and engage the edge of the card. The tube 12 is formed exteriorly with a longitudinal rib 19 extending substantially from the collar 15 to the zone 16, and with the clips 18 in place and clamping the card, the clips are constrained to turn with the turning of the head 13 and tube 12, no relative turning of the clips being permitted because the ends thereof adjacent to the rib 19 will engage the latter and the clips thus be arrested in their turning movement. The said rib has but slight projection beyond the cylindrical surface of the tube 12 and should the clips rise onto said rib the effect will be only to expand the clips slightly and place them under a greater tension to have a better gripping action on the paper of the card and resist any tendency to turn.

The clips, it is to be noted, are engageable with the cylindrical surface of the tube 12

to exert a holding action thereon independently of the rib 19 and are turnable on said cylindrical surface in either direction in adjusting and alining the card, the said rib acting solely as a stop to limit the turning movement of the clips.

The rolled card and the constraining band 17 thereof are readily accommodated in the case 14 to move into the case without obstruction in entering the lead and its holding means including the tube 12 in the said case. Thus, the attachment in no way interferes with the normal manipulation of the pencil to project or withdraw the lead 10.

Not only so but the external appearance of the pencil is normal in all respects. The casing 14 is shown with the usual clasp 14^a to engage a pocket in which the pencil is inserted.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I

Copies of this patent may be obtained for five cents each, by addressing the "Commissioner of Patents, Washington, D. C."

claim as new, and desire to secure by Letters Patent:

1. In a card holding means of the class described, a cylindrical element on which the card may be rolled, a longitudinal rib thereon, and an arcuate clip adapted to be sprung onto said element or removed therefrom to clamp or release the inner edge of the card, said clip being adapted to embrace said element for more than half its circumference and being turnable on the cylindrical surface of said element in either direction relatively to said rib, said rib being adapted to obstruct the turning of said clip on said element.

2. A card holding means of the class described comprising a casing, a cylindrical element in said casing on which the card may be wound, resilient clips embracing said cylindrical element for more than 180° and embracing the inner edge of the card to clamp the latter by the resiliency of the clips, said clips being turnable on said cylindrical element to adjust and aline the card, and stop means rigid on said cylindrical element and limiting the turning movement of said clips in either direction.

ALONZO B. SCOTT.
